MAGNETIC MATERIAL DETECTOR

Hugh E. Wurzbach, Magna, Utah

Application March 14, 1938, Serial No. 195,796

2 Claims. (Cl. 177—311)

This invention is concerned with an apparatus for detecting the presence of a moving body of magnetic material and pertains more particularly to an apparatus for the detection of a magnetic contaminant present in a mass of non-magnetic material while said mass of material is in motion, as for example, for the detection of a magnetic substance in a body of material on a moving conveyor belt, or on the person of an individual passing through a doorway or the like.

The principal object of the invention is to provide an apparatus for detecting the presence of a body of magnetic material such as small iron, steel, or nickel masses when they are present among non-magnetic materials which are being conveyed from one point to another or are being changed from one container to another.

In milling operations in which crushing machinery is used to pulverize the ore in the process of mill concentrate treatment it is not unusual for mine drills or parts thereof or parts of mining machinery to be present in the ore. If these parts are allowed to enter the crushing machinery with the ore they may cause considerable damage thereto, especially if they are of iron or steel. In large operations the ore is fed to the crusher or the like on conveyor belts which may be of considerable width, and it is a particular object of this invention to provide an apparatus for detecting the presence of a harmful foreign body in the relatively large body of ore moving on such conveyor belt, such detection being based on the magnetic properties of such foreign body and being effected by subjecting such a body of material to magnetic scrutiny.

A further object of the invention is to associate a suitable work circuit with the detecting apparatus so that certain operations will be performed upon the detection of a given sized moving body of magnetic material.

The apparatus may comprise a magnetic circuit which includes an air path of substantial dimensions interposed in the path of the body of magnetic material, and means are included in the magnetic circuit for producing a substantially constant magnetic flux therein. A detector coil is positioned so as to be linked by at least a portion of the flux in the magnetic circuit, and a work circuit is associated with the detector coil and is responsive to changes in voltage induced in the detector coil by changes of flux in the magnetic circuit. These changes in flux are produced by the changes in reluc-

tance of the magnetic circuit brought about by the movement of a magnetic body through the air path.

In some embodiments of my invention, particularly in the smaller embodiments thereof, the magnetic flux may be produced by permanent magnets. In all embodiments of my invention, I prefer to form the major portion of the magnetic circuit as an iron core which provides two or more pole members, and the air path portion of the magnetic circuit will comprise the air paths between the various pole members. The work circuit may comprise suitable means for causing the operation of a signal to indicate the presence of a body of magnetic material, or means for causing the stoppage of the machinery such as the conveyor belt or crusher, and if desired, means for recording and indicating the frequency at which magnetic material has passed a given point. The work circuit may also comprise means for removing the body of magnetic material, either directly or along with other material.

Further objects and advantages of the invention will either be specifically brought out in the following description or will be apparent therefrom. I have illustrated apparatus according to my invention in the accompanying drawings, and referring thereto:

Fig. 1 is a diagrammatic representation of a simple form of apparatus according to my invention;

Fig. 2 is a diagrammatic representation of a modified form of apparatus;

Fig. 3 is a diagrammatic representation of a further modified form of apparatus;

Fig. 4 is a partly sectional front elevation of a form of apparatus comparable to that shown in Fig. 2;

Fig. 5 is an end elevation thereof;

Fig. 6 is a sectional view thereof taken on line 6—6 in Fig. 4; and

Figs. 7 and 9 illustrate circuit arrangements useful according to the present invention, while Fig. 8 illustrates an application of the detector to a passageway or the like.

Referring to Fig. 1, a simple form of apparatus is shown as comprising a C-shaped core 1 of magnetic material such as transformer laminations providing a pair of opposing pole members 2 and 3 disposed on laterally opposite sides of a conveyor belt 4 upon which is a body of material 5. The magnetic circuit comprises the core 1 and the air path between the poles 2 and 3.

3, which air path is interposed in the path of material on the conveyor belt 4. The conveyor belt may be assumed to be moving either toward or away from the plane of the paper and the air path between the poles 2 and 3 may be considered as transverse to the conveyor belt and to the path of movement of the material carried thereon. The core 1 further comprises a winding 8 having terminals 7 and 8 which are adapted for connection to a suitable constant voltage source of direct current and which is adapted to energize the core 1 and the magnetic circuit to produce a substantially constant flux therein. The apparatus further comprises a pair of detector coils 9 and 10 mounted on the core 1, as at the pole members 2 and 3 and adapted to be linked by at least a portion of the flux in the magnetic circuit. The detector coils are shown connected in series and to a pair of terminals 11 and 12 which may be associated with a suitable work circuit.

Assuming now that the terminals 7 and 8 have been connected to a suitable direct current source and that a substantially constant flux is present in the magnetic circuit, there will be no appreciable voltage generated in the coils 9 and 10 and consequently no voltage across the terminals 11 and 12. As long as the material 5 on the conveyor belt 4 is practically non-magnetic in character, there will be no change in the magnetic circuit as the material passes through the air path between the pole members 2 and 3; however, if a small body of magnetic material is present in the material 5 it will, upon approaching the air path between the poles 2 and 3, decrease the reluctance of this air path and cause an abrupt change in the amount of flux linking the detector coils 9 and 10. This change in reluctance and the consequent change in flux will cause a voltage to be induced in either one or both of the coils 9 or 10 and a potential difference will be created between the terminals 11 and 12, which potential difference may be used to cause a work circuit connected to the terminals 11 and 12 to perform certain operations.

With the arrangement shown, the approximate center of the body of material carried on the conveyor belt 4 should lie approximately centrally between the two pole members 2 and 3, so that the effect produced by a body of magnetic material of a given size will be practically the same, irrespective of its position in the body of material 5. It should be mentioned that the relative dimensions of the parts of the core 1 depend largely upon the position of the belt 4 with respect to the core and upon the width and thickness of the material carried by the belt. These dimensions will thus be modified to meet various conditions, as will be apparent to those skilled in the art. In general, the spacing of the poles 2 and 3 will be less than the distance between one face and the back leg 1a of the core 1 at the opposite end of the coil 8. This condition will be adequately met if the distance A between the poles and the back leg 1a is not allowed to be less than the inter-pole spacing.

It may also be mentioned that numerous forms of connection may be made for the detector coils 9 and 10. For example, they may be connected either in series, or in parallel in additive or subtractive relation, depending upon the particular problem to be solved. It may also be mentioned that a single detector coil may be used in place of the two detector coils, and that

this detector coil may be placed in the same position as either one of the coils shown in Fig. 1, or that it may be placed at any position on the iron core 1, or in any other position in which it is linked by at least a portion of the flux in the magnetic circuit.

The energizing coil 8 may be of convenient size to produce an optimum amount of flux in the core 1, and its dimensions will depend largely upon the requirements of detection, the cross-section of the core 1, and the amount of economically available power. The detector coils 9 and 10 are preferably provided with a relatively large number of turns of fine wire, so that a maximum voltage will be generated by such coils for a minimum change in reluctance of the air path between the poles 2 and 3.

Referring to Fig. 2, I have shown a somewhat modified arrangement which is better suited for larger conveyor belts than the arrangement shown in Fig. 1. A conveyor belt is shown at 15 carrying a body of material 16 having a width transverse to the direction of movement of the conveyor belt which is relatively greater than its height, and a substantially E-shaped energizing core is shown at 17 arranged with its outer legs 18 and 20 and its central leg 19 extending in a direction transverse to the path of movement of the body of material on the conveyor belt and facing said path. The core 17 is elongated between the outer legs 18 and 20 in the direction of the transverse width of the moving body of material. Energizing coils are shown at 21, 22 and 23 on the respective legs 18, 19 and 20 and are preferably connected to terminals 24 and 25 in such manner as to produce a magnetic flux of one polarity in the legs 18 and 20 and a magnetic flux of opposite polarity in the center leg 19. An elongated detector core member 26 is shown spaced from the faces of the legs 18, 19 and 20 and positioned so that the flux from said legs passes through an air path of substantial dimensions which is interposed in the path of the body of material to subject the material to magnetic scrutiny, and also so that magnetic poles of the same polarity are produced in the opposite ends of the member 26. Detector coils 27 and 28 are shown wound on the detector core member 26 at positions spaced from the central portion of said core member. The coils 27 and 28 are shown connected in parallel and to terminals 29 and 30 which may be associated with a suitable work circuit.

The arrangement shown in Fig. 2 provides a somewhat more uniform distribution of flux through a large body of material as shown at 16, than the arrangement shown in Fig. 1. For best results the dimension B should be approximately equal to the distance between the faces of any one of the legs and the core member 26. If desired, the coils 27 and 28 may be connected in series or may be replaced by a single coil. It will be appreciated also that a detector coil may be placed at any position which is linked by at least a portion of the magnetic flux which flows in the circuit comprising the E-shaped core 17, the core member 26, and the air paths between said core members.

It may be advantageous in some instances to provide means for opposing the effect of voltage variations in the energizing circuit on the voltage induced in the detector coils, especially when the energizing circuit is subject to unavoidable voltage variations. In Fig. 9 an arrangement is

illustrated which may be used, by way of example, in conjunction with the apparatus shown in Fig. 2 and for purposes of illustration the detector core of Fig. 2 is shown provided with "buck-out" coils 27a and 28a which are connected in parallel and are adapted for parallel connection through terminals 24a and 25a to terminals 24 and 25 which are connected to the source of energizing current. The coils 27a and 28a are so proportioned and arranged as to produce fluxes which neutralize the fluxes produced in the core 28 by the energizing coils 21, 22, and 23. Thus voltage changes in the energizing circuit will produce no appreciable change in the flux linking the detector coils 27 and 28, while changes in reluctance of the magnetic circuit occasioned by the presence of a foreign magnetic body will produce an unbalanced circuit condition which causes a change in flux linkage of either one or both of the coils 27 and 28 and the production of a potential difference between the terminals 29 and 30.

In Fig. 3 I have shown an arrangement which is particularly applicable to conveyor belts which are carrying relatively thin layers of material. A conveyor belt is shown at 31 carrying a relatively thin layer of material 32, and a substantially E-shaped energizing core is shown at 33 with the legs 34, 35 and 36 thereof extending in a direction transverse to the path of movement of the body of material and facing said path. Coils are shown at 37, 38 and 39 carried by the respective legs 34, 35 and 36 and connected to power supply terminals 40 and 41 in such manner as to produce a magnetic flux of one polarity in the outside legs 34 and 36 and of opposite polarity in the center leg 35. Detector coils are shown at 42 and 43 wound on the respective legs 34 and 36 and connected in series and to a pair of terminals 44 and 45 which may be associated with a suitable work circuit. For best operation it is preferable that the level of the material above the core be located at a distance not in excess of about one-half the inter-pole separation represented by the dimension C. The magnetic circuit in this instance is represented by the E-shaped core 33 and the air path between the respective core legs which is interposed in the path of the material carried by the belt 31.

It will be appreciated that the coils 42 or 43 may be omitted and a single coil provided on the center leg 35. It will also be appreciated that coils may be provided on each leg and may be connected either in series or in parallel.

The above showings are primarily schematic, and are not intended to represent specific proportions or size of the respective elements of the apparatus. The presence of a foreign magnetic body, such as a bolt, in the conveyed material is indicated at F in Figs. 1 and 2, in exaggerated scale.

In Figs. 4 through 6 I have shown a preferred embodiment of the apparatus illustrated diagrammatically in Fig. 2. A conveyor belt is shown at 51 carrying material 52 having a width transverse to the direction of movement of the conveyor belt which is relatively greater than its height, and an E-shaped energizing core is shown at 53 provided with outer legs 54 and 56 and a central leg 55 upon which are wound suitable coils 57. The core 53 is elongated between the outer legs 54 and 56 in the direction of the transverse width of the belt 51. Since the conveyor belt 51 may be of considerable width, for example,

on the order of four feet, the mass of iron in the E-shaped core 53 may be considerable, and I have shown the core 53 clamped between angle members 58 which may be supported by a suitable foundation of concrete or the like. An elongated detector core is indicated at 60 and is shown as comprising a core 60 of soft iron rods upon which are wound suitably insulated detector coils 61. A length of iron pipe is shown at 62 between the coils 61 and similar lengths of pipe are shown at 63, which pipes serve as a casing for the core 60. The pipe 62 serves to space the coils 61, and the pipes 63, which may be secured to frame members 64, serve to position the coils with respect to the energizing core 53. Fiber washers 15 65 may be provided at the sides of the coils 61 to prevent damage thereto by the respective pipe ends. Caps may be provided at 66 to hold the core 60 in position and to provide a more finished appearance to the apparatus. Saddle clamps 67 20 are shown secured to the outside legs of the energizing core and the frame members 64 are shown as secured thereto.

The frame members 64, which are shown as iron channels, serve not only to support the core 25 59 but also to decrease the reluctance of the magnetic circuit established between the core 53 and the elongated core member 60, by decreasing the reluctance between the respective outside legs of the energizing core and the respective adjacent 30 ends of the detector core 60. This serves to increase the total flux between the center leg and the elongated core member. The connections to the energizing coils 57 and the detector coils 61 35 are omitted and it may be assumed that the connections are the same as shown in Fig. 2.

It will be appreciated that buck-out arrangements may be associated with the form of apparatus illustrated in Figs. 4 to 6, for example by providing buck-out coils on the core 60 arranged and energized in accordance with the showing in Fig. 9. It is also to be understood that other forms of buck-out devices may be employed in which the buck-out current supplied to the buck-out coils on the detector core 45 is obtained through the transformer action of coils provided on the energizing core. It is also within the contemplation of this invention to apply the buck-out effect directly on the potentials induced in the detector circuit as by taking 50 a potential responsive to the changes in potential of the energizing source and applying it in opposition to the detector coil potential. In these last-mentioned forms of buck-out devices, phase 55 relations of the various currents involved must be considered and suitable circuits employed when necessary to bring about the desired operation, as will be apparent to those skilled in the art.

A form of work circuit which may be associated with the detector coils of any of the above forms of apparatus, as by connection to the terminals 11 and 12 of Fig. 1, 28 and 30 of Fig. 2, or 44 and 45 of Fig. 3, is illustrated in Fig. 7, the positions 65 of the switches and relays corresponding to normal positions prior to starting the conveyor belt. Referring to said figure, a motor 71 which may be used to operate any of the conveyor belts shown herein, for example, the conveyor belt 51 70 in Fig. 4, is shown connected through a starting switch 72 to a three-phase power supply. One lead 82 of the power supply is shown connected through actuating coil 73 of a starting switch 72, thence through back contact 83 of a relay 74 75

- and connections 83' and 83'' to another lead 84 of the power supply, through a normally open push-button 78. Upon pressing push-button 78 the circuit of the coil 78 is closed, operating the starting switch 72 and maintaining coil 78 in energized relation by establishing contact through normally closed push-button 81, contact 85 of the starting switch 72 to line connection 84, rendering the push-button 78 inoperative.
- 10 A normally open relay is shown at 76 with its terminals 77 and 78 adapted for connection to a pair of the above-mentioned detector coil terminals. This relay should be of sufficient sensitivity to close its contact upon receiving a minimum voltage impulse from the associated detector coils in response to the presence of a body of magnetic material of given minimum size. Upon receiving an impulse this relay will momentarily close, energizing the coil of relay 74 for a sufficient time to establish connection at its front contact 86. This relay 74 may be of a type well known to the art which will close its contact in response to a short energizing impulse and will maintain its contact closed for a given time interval after the cessation of the impulse, returning to its position in contact with its front contact 83 at the end of the time interval. Such a relay may be dash-pot or motor operated after a manner well known to the art and need not be described in detail herein. The break of the circuit of relay 74 with its back contact 83 will break the circuit to coil 78, opening switch 72 to stop the motor 71. Closing of relay 74 with its front contact 86 will energize a warning horn 79 and operate the horn for the above-mentioned given time interval. Upon return of the relay 74 to a position contacting its back contact 83, the motor 71 may be set in operation again by pushing the start button 75.
- 40 The apparatus of this invention is not limited to use with conveyor belts but may be used in conjunction with hoppers, for example, to detect the presence of magnetic material in non-magnetic materials which are being transferred from one container to another through a hopper. The apparatus may also be used for detecting dangerous weapons or steel tools or the like carried by persons; and referring to Fig. 8, a doorway is shown at 91 through which persons suspected of carrying contraband magnetic materials are caused to pass. An energized core member 92 is positioned at one side of the doorway 91, and a detector core member 93 carrying detector coils 94 is positioned at the other side of the doorway.
- 55 Magnetic frame members 95 are positioned above and below the door frame and serve to connect the cores 92 and 93. This arrangement corresponds in general to the arrangement shown in Fig. 4 and may be connected to operate in the same manner.
- 65 It should be noted that in any of the forms described above the core members may be oriented in any direction with respect to the horizontal in accordance with the conditions encountered as long as a substantially constant magnetic flux is produced in an air path which is inter-

posed in the path of the material suspected of containing magnetic bodies and a detector coil is arranged to be linked by at least a portion of the flux which is influenced by changes in the magnetic reluctance of the air path.

It should be noted that in general there will be bodies of magnetic material disposed at various positions about the detecting apparatus, in the form of machinery, supporting rollers for conveyors, and other iron or steel objects. Such objects will generally not affect the operation of the detecting apparatus as long as they are stationary or do not act to produce a rapid rate of change in the reluctance of the magnetic circuit linked by a detector coil.

15 It will be appreciated that numerous forms of core and detector coil arrangements will become apparent to those skilled in the art and I do not choose to be limited to the forms shown and described herein, but rather to the scope of the appended claims.

I claim:

1. An apparatus for subjecting a relatively large moving body of material to magnetic scrutiny, such body of material being carried on a conveyor member and having a width which is relatively greater than its height as measured transversely of the direction of movement thereof, for the detection of the presence of a body of magnetic material in such moving body of material, which comprises: a substantially E-shaped core of magnetic material having outer legs and a central leg extending toward and in a direction transverse to the path of movement of said material, said core being elongated between said outer legs in the direction of the transverse width of the moving body of material; means for energizing the legs of said E-shaped core to produce a magnetic flux of one polarity in the outside legs thereof and a magnetic flux of opposite polarity in the center leg thereof; an elongated core member spaced from said legs and positioned so that the flux from said legs passes through an air path of substantial dimensions interposed in the path of said body to produce magnetic poles 40 of the same polarity in opposite ends of said core member; detector coils wound on said elongated core member at positions spaced from the central portion thereof; and a work circuit associated with said detector coils and responsive to changes 45 in voltage induced in said coils by changes in reluctance in said air path produced by movement of a magnetic body through said air path.

2. An apparatus as set forth in claim 1, and also comprising a frame member of magnetic material carried by each outer leg of said E-shaped core and serving to position said elongated core member and secured thereto adjacent an end, whereby the reluctance of the magnetic circuits established between said E-shaped core and said elongated core member is decreased between said opposite ends of said elongated core member and said outer legs, and the flux between said central leg and said elongated core member is increased.

65 HUGH E. WURZBACH.
